UNITED STATES PATENT OFFICE.

SAMUEL DUNCAN BLACK AND ALONZO G. DECKER, OF BALTIMORE, MARYLAND,
ASSIGNORS, BY MESNE ASSIGNMENTS, TO SECOND NATIONAL BANK OF BALTI-
MORE, TRUSTEE, OF BALTIMORE, MARYLAND.

DESIGN FOR A HOUSING FOR ELECTRIC AIR COMPRESSORS AND MOTORS.

57,812.

Specification for Design.

Patented May 10, 1921.

Application filed June 6, 1919. Serial No. 302,345. Term of patent 14 years.

To all whom it may concern:

Be it known that we, SAMUEL DUNCAN BLACK and ALONZO G. DECKER, citizens of the United States of America, and residents of the city of Baltimore, State of Maryland, have invented a certain new, original, and ornamental Design for a Housing for Electric Air Compressors and Motors, of which the following is a specification.

In the accompanying drawing we have illustrated a housing for a motor and air compressor embodying the features of our invention.

Figure 1 is a perspective view taken from the side, and

Fig. 2 is an end elevation.

What we claim and desire to secure by Letters Patent is:

The design for a housing for electric air compressors and motors substantially as shown.

Signed by us at Baltimore, Maryland, this 3rd day of June, 1919.

SAMUEL DUNCAN BLACK.
ALONZO G. DECKER.
